WILLIAM H. NICKERSON, OF NEWTON, MASSACHUSETTS

METHOD OF AND MEANS FOR MAKING PRONGED SHEET-METAL STIFFENERS

Application filed May 27, 1929. Serial No. 366,445.

This invention relates to the manufacture of pronged sheet metal stiffeners, such as those commonly used for reinforcing the shank portions of shoe soles, the stiffeners being formed by severing an elongated sheet metal strip into sections, each constituting a stiffener having prongs at its opposite ends adapted to be anchored in a member of a shoe bottom.

The chief object of the invention is to reduce to a minimum the waste of material involved by the operation of forming integral prongs on the opposite ends of stiffeners cut from a strip of indeterminate length.

Of the accompanying drawings forming a part of this specification,—

Figure 1 is a longitudinal sectional view of stiffener forming means adapted to make pronged stiffeners in accordance with my invention.

Figure 2 is a section on line 2—2 of Figure 1, and a plan view of the parts below said line.

Figure 2a is a fragmentary section on line 2a—2a of Figure 2.

Figure 3 is a bottom plan view of the upper element of the means shown by Figure 1.

Figure 4 is a section on line 4—4 of Figure 1.

Figure 5 is a section on line 5—5 of Figure 1.

Figure 6 is a perspective view, showing portions of the punching mechanism, the combined severing and inner bending mechanism, and the outer bending mechanism hereinafter described.

Figure 6a is a perspective view, showing a portion of one of the members shown by Figure 6.

Figure 7 is a perspective view of a portion of the strip, showing a punched orifice therein, and by dotted lines, the location of the severing cuts which detach a stiffener from the strip.

Figure 8 is a perspective view, showing a portion of the strip after a stiffener has been severed therefrom.

Figure 9 is a perspective view, showing the prongs on the inner end portion of the detached stiffener.

Figure 10 is a perspective view of a completed stiffener.

The same reference characters indicate the same parts in all of the figures.

In the drawings 12 designates an elongated strip of sheet metal, preferably steel, of a thickness suitable for the stiffener which reinforces the shank portion of a shoe bottom, the strip being of uniform width and of any desired length.

My improved method includes the steps next described. I longitudinally feed the strip step by step, and while it is at rest, I punch it to form an orifice 13 having edges spaced from the edges of the strip by necks 14 of uniform width, each neck containing material for two pointed prongs. After the strip is punched, it is moved endwise to remove the orifice 13 from the punches, and held in a fixed position while the necks are being converted into prongs. In converting the necks I split the same obliquely from end to end along the dotted lines 16 (Figure 7), thereby detaching an incomplete stiffener from the strip and forming edges of pointed prongs 17 on the leading end of the strip, and edges of pointed prongs 18 on the detached end of the incomplete stiffener. The opposite end of the stiffener has a pair of pointed prongs 17, originally formed on the leading end of the strip. The prongs 17 and 18 are bent outward from the plane of the stiffener, so that the completed stiffener shown by Figure 10 has outstanding prongs 17 at one end of its body portion 19, and outstanding prongs 18 at the opposite end. The only waste involved is that involved in punching the blank 15 (Figure 6) from the strip.

The necks 14 are preferably split, and the inner prongs 18 bent by a single operation, as hereinafter described, said operation detaching a partially formed stiffener from the strip and bending the inner prongs 18 from the inner end of the detached stiffener, the prongs 17 on the leading end of the strip remaining unbent until they become the prongs at the opposite end of the detached stiffener.

The necks 14 are preferably split, and the inner prongs 18 bent by a single operation, as hereinafter described, said operation detaching a partially formed stiffener from the strip and bending the inner prongs 18 from the inner end of the detached stiffener, the prongs 17 on the leading end of the strip remaining unbent until they become the prongs at the opposite end of the detached stiffener.

I will now describe the preferred means for practising the method above described.

21 designates a fixed element, which is the bed of a press. 22 designates a movable element, which is a press platen reciprocated by power, toward and from the bed. The bed 21 is provided with a punching mechanism including a base member 23, fixed to the bed and provided with a female punch 24, and a head 25, supported by springs 26, and provided with a male punch 27, said punches being adapted to form the orifice 13 when the head 25 is depressed by the descent of the platen 22, which contacts with and depresses the head. The bed 23 is provided with a guide 28 (Figure 4) for the strip 12. Suitably spaced from the punching mechanism is a combined severing and inner bending mechanism, adapted to split the necks 14, and bend downwardly the inner prongs 18. Said mechanism includes a pair of movable cutting and bending members 29, carried by the platen 22 and a group of fixed cutting and bending members 30 and 31, attached to the bed 21, and adapted to cooperate with the members 29, as indicated by Figure 6. When the platen 22 descends, the members 29 cooperate with the members 30 in splitting the necks 14, and with the member 31 in downwardly bending the inner prongs 18. Figure 6 shows the members 29 by dotted lines, in their depressed position, and by full lines in their raised position. Fig. 6a shows the fixed members 30 and 31 separated from the movable members 29.

Spaced from the severing and inner bending mechanism, is a pair of outer bending members adapted to bend from the outer end of the detached stiffener the outer prongs 17, originally formed on the strip 12. Said members include a fixed member 33, attached to the bed 21, and a movable member 34, carried by the platen 22. When the member 34 descends, as indicated by dotted lines in Figure 6, it cooperates with the member 33 in bending the prongs 17.

The stiffener provided with prongs as described, may be molded to impart thereto the longitudinal curvature and the rib 20 shown by Figure 10, by a fixed molding die 35, attached to the bed 21, and a movable molding die 36, attached to the platen 22.

Any suitable means may be provided for feeding the strip 12, for example, feed rolls 38, shown by dotted lines in Figure 1, said rolls being intermittently driven.

The completed stiffener may be removed by any suitable means. Figures 1, 2 and 2a show removing means including a finger 39 pivoted at 40 to a block 41, fixed to the bed 21, and provided with a tail piece 42, arranged to be depressed by the platen 22 when the latter descends. The finger 39 normally projects under the body portion 19 of a completed stiffener, as shown by full lines in Fig-

ure 2a, and when moved to the position shown by dotted lines by the descent of the platen, displaces the stiffener so that it may be conveniently removed.

I claim:

1. That improvement in the method of making pronged stiffeners from an elongated sheet metal strip, which consists in punching the strip to form an orifice therein having edges spaced from the edges of the strip by necks of uniform width, each neck containing material for two pointed prongs, splitting said necks obliquely to detach a stiffener from the strip and form a pair of pointed prongs on the leading end of the strip, and a pair of pointed prongs on the detached end of the stiffener, the opposite end of the stiffener having a pair of pointed prongs originally formed on the leading end of the strip, and outwardly bending said prongs from the plane of the stiffener.

2. Means for making pronged stiffeners from an elongated sheet metal strip, comprising a fixed bed, a platen movable toward and from the bed, a punching mechanism including a base having a female punch and attached to the bed, a spring-supported head on the bed having a male punch and movable by the platen to cause said punches to punch an interposed strip, the punching dies being adapted to form an orifice in the strip having edges spaced from the edges of the strip by necks of uniform width, each neck containing material for two pointed prongs, a combined severing and inner bending mechanism spaced from the punching mechanism, and adapted to split said necks obliquely and thereby detach a stiffener from the strip and form a pair of pointed prongs on the leading end of the strip, and a pair of pointed prongs on the detached end of the stiffener, said mechanism including movable cutting and inner bending members carried by the platen, and fixed cutting and inner bending members attached to the bed, said members being adapted to bend the pair of pointed prongs from the detached end of the stiffener, and a pair of outer bending members spaced from the severing and inner bending mechanism and adapted to bend from the outer end of the detached stiffener the pair of outer prongs originally formed on the leading end of the strip, one of said outer members being carried by the platen, and the other fixed to the bed.

In testimony whereof, I have affixed my signature.

WILLIAM H. NICKERSON.
